Design No. 13,473, dated December 5, 1882.

UNITED STATES PATENT OFFICE.

GEORGE G. WHITE, OF NEW YORK, N. Y., ASSIGNOR TO THE NEW YORK CONSOLIDATED CARD COMPANY, OF NEW YORK.

DESIGN FOR A PLAYING-CARD.

SPECIFICATION forming part of Design No. 13,473, dated December 5, 1882.

Application filed October 28, 1882. Term of patent 14 years.

To all whom it may concern:

Be it known that I, GEORGE G. WHITE, a citizen of the United States, residing at the city of New York, in the county and State of New York, have invented and produced a new and original Design for one of a Pack of Playing-Cards, known as the "Ace of Spades," of which the following is a description, reference being had to the accompanying drawings, forming a part thereof.

The leading feature of my design consists in a solid figure or emblem of an ace of spades, having a heavy border following the contour of the ace spot or pip, said border having inner and outer thin lines of the same configuration. Upon the face of the ace-spot appears an ornamental design consisting of two doves, bow and arrows, and flowers, together with a flowing ribbon. The ace-spot is surrounded with floral ornamentation, a basket appearing to the left and bag-pipes to the right thereof, above which is a coronet. At the upper part of the floral ornamentation and as if seated thereon, on the left side, is a female figure, and on the right a male figure. Below the ace-spot, 25 on ribbon scrolls, appear the following words: "Gem No. 53 N. Y. Consolidated Card Co.;" but these words form no essential part of my design, and are not herein claimed.

What I claim is—

The design for the ace of spades of a pack of cards, as shown and described, the same consisting of an ace-spot surrounded with one heavy and two lighter configurative borders, 35 interior and exterior floral and musical ornamentation, the representation of a female and male figures, an upper coronet, and lower ribbon scrolls, all arranged as described.

GEORGE G. WHITE.
